ASH TRAY

Firman G. Hoyt, 907 McGrann Blvd.,
Lancaster, Pa. 17601

Filed Nov. 21, 1966, Ser. No. 4,745

Term of patent 14 years

(Cl. D85—2)

FIG.1.

FIG.3.

FIG.2

FIG.4.

FIG.5.

FIG.7.

FIG. 1 is a plan view of an ash tray showing my new design;

FIG. 2 is a fragmentary side elevational view of the ash tray shown in FIG. 1;

FIG. 3 is a left end view of the ash tray shown in FIG. 1;

FIG. 4 is a right end view of the ash tray shown in FIG. 1;

FIG. 5 is a perspective view of the upper portion alone;

FIG. 6 is a perspective view of the lower portion alone;

and

FIG. 7 is a perspective view of the lower portion of an ash tray showing the new design wherein the handle element is executed as a solid planar member.

I claim:

The ornamental design for an ash tray, substantially as shown and described.
